UNITED STATES PATENT OFFICE.

REGINALD FORWOOD, OF NEW YORK, N. Y.

PARALLEL-RULER.

SPECIFICATION forming part of Letters Patent No. 443,959, dated December 30, 1890.

Application filed August 11, 1890. Serial No. 361,705. (No model.)

To all whom it may concern:

Be it known that I, REGINALD FORWOOD, a subject of the Queen of Great Britain, residing at the city of New York, in the county 5 and State of New York, United States of America, have invented a new and Improved Ruler, of which the following is a full, clear, and exact description.

My invention relates to a ruler device to be 10 used as a guide to a pen, pencil, or brush in producing straight and parallel lines at the same or at variable distances apart; and the invention has for its object to provide a simple, inexpensive, and efficient device of this 15 character.

The invention consists in certain novel features of construction of the ruler, as herein-after described and claimed.

Reference is to be had to the accompanying 20 drawings, forming a part of this specification, in which similar letters of reference indicate corresponding parts in all the figures.

Figure 1 is a perspective view of my improved ruler provided with three parallel 25 rollers. Fig. 2 is an enlarged side view of one end of the ruler with parts in vertical section on the line xx in Fig. 3. Fig. 3 is an end view of the ruler, and Fig. 4 is an end view of a modified form of the ruler having but two 30 parallel rollers.

I will first particularly describe the preferred form of ruler having three triangularly-disposed parallel rollers, and shown in Figs. 1, 2, and 3 of the drawings.

35 The three rollers A A A may be made of any suitable material or materials, and may have any preferred diameter and length. I may journal the rollers to end bearings or supports B B in any approved manner, 40 preferably by means of screws a , which are threaded into the ends of the rollers and run loosely in the bearings. I prefer at present to make the rollers of suitable metal tubing having plugs a' inserted in their ends to receive the screw-journals, and as shown best in Fig. 2 of the drawings.

It will be noticed that the end bearings B B do not extend marginally at any point beyond the peripheries of the triangularly-disposed rollers. Hence the ruler may be set or 45 run along on any two of the rollers to allow a

ruling pen or pencil to be guided alongside of either or both lower rollers for making a straight line, or parallel straight lines at any desired distance apart, while the ruler is held 55 at rest by pressure on its uppermost roller.

To assure greater convenience and accuracy in ruling parallel lines at equal distances apart I have provided one or all of the rollers, and it may be at one or at both ends, with a 60 series of peripheral graduations C, which are set or gaged to an index-pointer b on the adjacent end bearing or support B, and whereby after one line is drawn the ruler may be rolled until the next graduation - mark 65 appears in line with the index-pointer on the bearing, when the next line will be ruled off. The drawings represent all three of the rollers A, provided at one end with a scale of graduation-marks C, and the adjacent bearing B has three index-pointers or angular lugs b , which extend to the graduations of the rollers. These graduations may be spaced differently on the different rollers to allow 70 ruling of evenly-spaced parallel lines at three 75 different distances apart.

Fig. 4 of the drawings shows that some of the constructive principles of my invention may be embodied in a ruler having but two rollers A' A', journaled by axle-pins a to 80 end plates or bearings B', which have index-pointers b' extending to peripheral graduations of the rollers. These end bearings or supports B', like the ones B, first described, do not extend marginally beyond the peripheries of the rollers. This ruler, like the triple-roller device, is used by rolling it along the paper or object to be ruled, and then applying the pen or pencil alongside of either of the rollers, as will be readily understood. 85

Having thus described my invention, I claim as new and desire to secure by Letters Patent—

1. A ruler comprising parallel rollers journaled in end bearings or supports which do 95 not extend marginally beyond the peripheries of the rollers, substantially as described.

2. A ruler comprising end bearings or supports and three triangularly-disposed parallel rollers journaled thereto, substantially as de- 100 scribed.

3. A ruler comprising end bearings or sup-

ports and three triangularly-disposed parallel rollers journaled thereto, said bearings not extending marginally beyond the peripheries of the rollers, substantially as described.

5. A ruler comprising end bearings or supports and parallel rollers journaled thereto and each provided with peripheral graduations, the adjacent bearing having an index-pointer next each roller-graduations, substantially as described.

10. A ruler comprising end bearings or sup-

ports and three triangularly-disposed parallel rollers journaled thereto and provided with peripheral graduations, said bearings not extending marginally beyond the peripheries of the rollers and provided with one or more index-pointers next the roller-graduations, substantially as described. ¹⁵
